(57) **CLAIM**

The ornamental design for a teleconference room, as shown and described.

DESCRIPTION

FIG. 1 is a right side perspective view of a teleconference room;

FIG. 2 is a front view thereof;

FIG. 3 is a front view thereof, showing a closer view of the front of the teleconference room;

FIG. 4 is a left side perspective view thereof; and,

FIG. 5 is a close up left side view of a front region in the teleconference room.

The broken lines showing of various regions and the unshaded areas therein are for the purpose of illustrating the article and form no part of the claimed design.

The broken lines showing the chairs in the teleconference room are for the purpose of illustrating the article and form no part of the claimed design.

The broken lines showing front wall features are for the purpose of illustrating the article and form no part of the claimed design.

The broken lines showing ceiling and lighting features are for the purpose of illustrating the article, and form no part of the claimed design.

The broken lines showing displays are for the purpose of illustrating the article and form no part of the claimed design. The broken lines showing cameras are for the purpose of illustrating the article and form no part of the claimed design. The broken lines showing a mouse connection are for the purpose of illustrating the article and form no part of the claimed design.
